UNITED STATES PATENT OFFICE

119,292

DESIGN FOR A SCALE

Albert J. Watling, Chicago, Ill., assignor to
William Watling, Chicago, Ill.

Application December 8, 1939, Serial No. 88,777

Term of patent 7 years

To all whom it may concern:

Be it known that I, Albert J. Watling, a citizen of the United States, residing at Chicago, in the county of Cook and State of Illinois, have invented a new, original, and ornamental Design for Scales, of which the following is a specification, reference being had to the accompanying drawing, forming part thereof.

Fig. 1 is a front elevation of a scale embodying my design;

Fig. 2 is a side elevation of my scale, and
Fig. 3 is a plan view of my scale.

The characteristic features of my design reside in the portions shown in full lines.

I claim:

The ornamental design for a scale, as shown and described.

ALBERT J. WATLING.
